(57) **CLAIM**

The ornamental design for a catch can, as shown and described.

DESCRIPTION

FIG. 1 is a top front perspective view of a catch can showing our new design;

FIG. 2 is a right view thereof;

FIG. 3 is a left view thereof;

FIG. 4 is a front view thereof;

FIG. 5 is a back view thereof;

FIG. 6 is top view thereof; and,

FIG. 7 is a bottom view thereof.

The broken lines in the drawing figures show portions of the catch can which form no part of the claimed design.

The shade lines in the figures show contour and not surface ornamentation.
